[57] ABSTRACT

The perforation punching is effected by rotary punching tools secured to driving shafts and including a first tool provided with readjustable punch pins mounted in a receiving body and a cooperating second tool provided with punch dies. The punch pins are regrindable by a grinding attachment, to tangency of their working ends with a common circle concentric with the axis of rotation of the first tool. The grinding attachment is mounted adjustably on the machine frame and permits regrinding the pins without removing the tool from its working position. The pin resetting device is mounted in the receiving body coaxial with the driving shaft of the first tool and acts simultaneously on all of the pins. The resetting device is actuatable, for rotation, by an actuating means which is externally accessible. In one embodiment, the pins are of equal length and have oblique inner ends which are resiliently biased against a conical ring which can be moved axially by a gear wheel threadedly engaged with the receiving body and rotated by a pinion which, in turn, has an externally accessible drive shaft. In another embodiment, the pins are of unequal and gradually increasing length, and their inner ends engage the spiral periphery of a member rotatably mounted in the receiving body and having a gear hub engageable with an actuating pinion which may be rotated from the exterior of the machine.

ROTARY PRINT PRESS INCLUDING A DEVICE FOR PUNCHING ROWS OF PERFORATIONS IN CONTINUOUS PAPER WEBS

FIELD AND BACKGROUND OF THE INVENTION

This invention relates to rotary printing presses having devices for punching rows of perforations in continuous webs, the devices being in the form of rotary punching tools secured to driving shafts and including a first tool provided with readjustable punch pins mounted in a receiving body and a second tool provided with punch dies, and, more particularly, to such a rotary printing press in which all the pins may be radially adjusted simultaneously and may be re-ground so that their outer ends are tangent to a common circle concentric with the axis of rotation of the first tool, by means of a grinding attachment adjustably mounted on the machine frame.

Up to the present, rotary perforation punching tools, used in rotary printing presses, are of the type in which each individual pin of an upper tool is clamped in a respective bore of the receiving body by a screw, from the front side. After a certain service time, the pins are worn down to the extent that it is no longer possible to obtain uniform perforations. To reset the tool, it has been necessary individually to release each pin, readjust its protruding length, and to clamp the pin in position again. This work still occurs outside the rotary press. Thus, for resetting, the upper tool must be removed from the shaft and, at a suitable working place, each pin must be reset to obtain a length as accurate as possible and to be reground on a separate machine. However, because the printer is in no way familiar with the metal removing work and also does not possess any machine tools, it has been usual to hand over the reset upper tool to a grinder who effects the grinding of the pins on the grinding machine available at another location. It is only thereafter that the upper tool can be remounted into the rotary press.

This necessary sequence of working operations is extremely time-consuming, and also the rotary press is out of service during the working operations. The loss of working hours resulting from the operation is frequently very high.

It is indispensable, for the mentioned sequence of adjusting operations, first to reset the length of the worn pin and only then to proceed with the grinding. An attempt to reset the centrical working outer line of the tool by regrounding the worn pins without a previous resetting would inevitably result in a loss of the piercing effect, because the distance between the axes of the upper and lower tools in the rotary press is set and unchangeable.

SUMMARY OF THE INVENTION

The present invention is directed to the problem of avoiding the previously necessary removal of the upper tool, and to reduce substantially the readjusting time for punching tools from the resetting thereof to the grinding thereof.

In accordance with this invention, this problem is solved by providing, in the receiving body and coaxially of the driving shaft, a resetting device acting simultaneously on all of the pins and which may be actuated by actuating means accessible exteriorly of the printing

press and which furthermore is capable of displacing the pins radially by equal distances, and by mounting the grinding device on a cross beam of the frame of the rotary press, the cup wheel of the grinding device being adjustable to the reset pins of the upper tool while the latter remains in its working position.

The invention makes it possible to reset all of the pins of a punching tool simultaneously by the same distance without removing the tool from the rotary press, and thereafter immediately to regrind the reset pins to accurate tangency of their outer or working ends with a common circle concentric with the axis of rotation of the tool. Both the resetting operation and the regrounding operation may be performed in a very brief period of time and, for the grinding, there may be utilized the driving mechanism already provided in the press for the punching tools, so as merely to run the machine at a lower speed and without the paper web therein. In comparison with the hitherto necessary removal operation, the accuracy of the grinding is improved because the upper tool to be reground remains on its shaft in its working position. The grinding cup wheel is driven separately, and need only be adjusted to the exact diameter of the punching tool, that is, to the exact diameter of the common circle concentric with the axis of rotation of the tool. A reciprocating movement of the grinding cup wheel during grinding is not necessary, because the cup does not produce tooling marks.

Advantageously, grits and ground way material are evacuated through an auxiliary nozzle connected to a suction or exhaust device which is already provided on the rotary press for removing the perforation waste.

In one embodiment of a resetting device in accordance with the invention, mounted in the receiving body of the upper tool, the receiving body comprises a hub having an external thread, and a gear having a corresponding internal thread is screwed on to the external thread, the gear being provided with a hub bearing a conical ring, which is fixed against axial displacement relative to the gear, and which has a conical surface against which rests the inner ends of pins having equal lengths. The inner ends of the pins are provided with corresponding oblique surfaces and subjected to the bias of compression springs. The gear meshes with an axially fixed rotatable adjusting pinion mounted in the receiving body, and secured to a shaft which constitutes an externally accessible actuating means.

In the first embodiment of the resetting device, the pins are always equal in length and remain in the tool until all the pins are entirely used up. The maximum resetting is effected by biasing the inner ends of the pins against the conical surface in the zone of its maximum diameter. The adjustment resetting path of the conical ring is limited by a stop screw cooperating with the gear and secured by a lock nut. When the gear is moved in the opposite direction, all of the pins are retracted uniformly into the receiving body, under the spring bias. Thus, the resetting device permits putting an upper tool, equipped with perforation pins, out of operation, so that it will not perform any perforating operation. In this case, also, the resetting device makes it unnecessary to remove a punching tool from its shaft when it is not to be used.

To obtain the possibility of easy resetting of the pins of the punching tool in any working position of the latter, it is advantageous to provide two equivalent adjusting pinions at diametrically opposed locations, where

they may be actuated selectively by means of squared ends on the respective shafts.

In another embodiment of the resetting device, the receiving body has associated therewith a disc having a spiral external periphery with a regular gradient, and which is mounted on the hub of a covering flange and provided with another hub in the form of a gear. Pins of gradually different lengths and overall cylindrical shape are biased against the spiral peripheral surface of the disc. The uniformly graduated length differences of the pins are equal to one another, and correspond to the spacing of the pins on the receiving body as well as to the gradient of the spiral. A clamping mechanism is associated with each pin and the gear is engaged with an adjusting pinion which is mounted in the receiving body so as to be restrained against axial movement, and having a shaft provided with actuating means accessible from the exterior of the press.

As compared to the first embodiment, the second embodiment of the resetting device has the advantage that, of all the pins, in each case only the shortest one is replaced as soon as its resetting length is used up. After releasing the clamping mechanism, such a pin can easily be removed from its reception bore, and, after turning the disc through one pitch, the worn pin can be replaced by a new pin which then will be the longest pin.

With respect to the clamping mechanism, it is advantageous to provide, transversely of the reception bore of each pin, a larger bore partially intersecting the reception bore and receiving a tapered locking bolt whose oblique surface, in the clamping position, engages the pin owing to the pressure of disc springs which are mounted on the bottom of the larger bore at the rear end surface thereof. On the front portion of the bore, a tapped bore is provided coaxial with the larger bore, and a back-pressure screw may be threaded into the tapped bore to release the clamping of the pin. To accomplish resetting, it is sufficient to screw in the back-pressure screw at the location corresponding to the shortest worn pin, and that only for the time necessary to loosen the pin and replace it by a new one. Thus, the back-pressure screw is only an auxiliary tool which is removed immediately after a pin has been replaced.

An object of the invention is to provide, in a rotary printing press, an improved device for punching rows of perforation in continuous paper webs.

Another object of the invention is to provide such a device in which punching pins may be reset and reground without removal of a supporting body from the press.

A further object of the invention is to provide such a device in which the "down time" for resetting and regrounding the punching pin is reduced to a minimum and is very considerably less than that presently required.

Another object of the invention is to provide such a device in which all of the pins can be simultaneously reset through the same radial distance by actuating means accessible from the exterior of the printing press.

For an understanding of the principles of the invention, reference is made to the following description of typical embodiments thereof as illustrated in the accompanying drawings.

BRIEF DESCRIPTION OF THE DRAWINGS

In the Drawings:

5 FIG. 1 is a simplified schematic representation of a rotary printing press including an adjustable upper tool of a punching device and a grinding attachment mounted above the tool;

10 FIG. 2 is an enlarged view, partly in section, illustrating the punching tools and the grinding attachment of FIG. 1 in greater detail;

15 FIG. 3 is a top plan view of the grinding attachment and corresponding to FIG. 2;

20 FIG. 4 is an end elevation view of a first embodiment of the resetting device and the upper tool, as shown in FIG. 2;

25 FIG. 5 is a cross-sectional view, taken along the line V—V of FIG. 4, with the pins being in working position;

30 FIG. 6 is a similar view with the pins being in a non-working and retracted position;

35 FIG. 7 is an end elevation view, partly broken away, of another embodiment of the resetting device shown in FIG. 2;

40 FIG. 8 is an enlarged cross-sectional view taken along the line VIII—VIII of FIG. 7;

45 FIG. 9 is an enlarged sectional view illustrating the pin clamping means of FIG. 8 with the pins in their working positions; and

50 FIG. 10 is a view similar to FIG. 9, but illustrating the pins as released.

DESCRIPTION OF THE PREFERRED EMBODIMENT

Referring to FIG. 1, the rotary press illustrated therein operates on a roll 1 of paper from which there is drawn a web 2 which passes through printing units 3, a forwarding mechanism 4, three perforators 5, and a set of punching tools 6 to the delivery 7. Punching tools 6 include an upper tool 8 and a lower tool 9 both carried by respective driving shafts mounted in frame 10 of the machine. Upper tool 8 is provided with punching pins 11, and lower tool 9 is provided with the corresponding number of punching dies 12. The grinding attachment, generally designated at 13, is provided above upper tool 8 and is equipped with a cup grinding wheel 14 rotatable about a vertical axis.

As best seen in FIGS. 2 and 3, grinding attachment 13 is mounted adjustably on the cross beam 15 of machine frame 10, by means of a slide 16 which can be clamped in its adjusted position by clamping screws 17 operated by levers 18. Slide 16 supports a column 19 serving as a guide for a vertically adjustable carriage 20 and, for adjusting carriage 20, an axially fixed spindle is mounted on column 19 and is threadedly engaged in an internal thread of carriage 20. Carriage 20 supports the bracket 22 and a motor 23 driving the spindle 25 of a cup wheel 14 through the medium of a V-belt and pulley arrangement 24. Grinding face 26 of cup grinding wheel 14 is adjustable to the regrinding diameter D of pins 11 and to any upper tool 8 because, by virtue of its mounting on cross beam 15, it may be brought into any desired position.

Upper and lower tools 8 and 9 punch or pierce rows of perforations 27 into web 2. The axial spacing of the punching tools on their shaft is adjustable. FIG. 3 illustrates how upper tools 8 are mounted on their driving shaft 28. Shaft 28 is formed with a longitudinal keyway

or groove 29 receiving keys which have not been shown in FIG. 3. To secure the two tools at a spacing corresponding to the spacing of the desired perforations 27, respective screws 30 are tightened against the keys. Lower tools 9 are secured to their driving shafts in an inanalogous manner.

Perforating or punching pins 11 inserted in upper tool 8 may be reground while tool 8 remains in its working position in the rotary press. The grits and the like from the regrinding operation are evacuated to a suction head 31 connected through a flexible pipe 33 to an exhauster 32, as shown in FIG. 1. Such an exhauster or suction device is usually provided, in any case, for removing paper shavings and the like and is driven by an electric motor 34.

FIGS. 4, 5, and 6 illustrate a first embodiment comprising a resetting device 34 mounted in upper tool 8 which is equipped with pins 11. Upper tool 8 is secured to its drive shaft 28 by means of a clamping screw 36, corresponding to the clamping screw 30 of FIG. 3, and bearing against a key 37 inserted into a longitudinal groove 38 corresponding to groove 29 of FIG. 3.

Tool 8 comprises a receiving body 39 including a hub 41 which is externally threaded. A gear 42 is internally threaded to engage the threaded hub 41, and is provided with a hub 43 bearing a conical ring 44 which is fixed against axial movement by a shoulder of hub 41 and by a snap ring 45, so that conical ring 44 is fixed against axial movement relative to gear 42. The inner ends of pins 11 are provided with heads 47 having oblique contact surfaces corresponding to the conical surface 46 of ring 44, and biased against the conical surface by compression springs 48, which are preferably disc springs. Through gear 42, conical ring 44 is adjustable axially by rotation of a pinion 49 which is mounted in receiving body 39 in an axially fixed position. To retain pinion 49 against axial displacement, a set screw 50 engages in an acute-angled circular groove 51 of the pinion shaft. The pinion shaft terminates in a square outer end 52 which is externally accessible to actuate pinion 49 and, thus, to actuate resetting device 34.

A stop screw 53 in association with a lock nut 54 is threaded into receiving body 39 and directed into engagement with gear 42 for defining the resetting range of gear 42 and conical ring 44. In the opposite direction, the resetting range of gear 42 and ring 44 is limited by an annular stop 55 secured to the left-hand frontal surface, as shown in FIGS. 5 and 6, of hub 41.

In this embodiment of the invention, all the pins 11 have the same length. In their working position, the pins protrude from the periphery of receiving body 39 in accordance with the setting effected by the pinion 49, as shown in FIG. 5. The protrusion of the pins is limited by the end position of gear 42 as set by screw 53 in lock nut 54. In this extreme position, the pins are ground exactly to the desired diameter of the working circle of the outer end of the pins, by means of the grinding attachment described above.

To retract pins 11 from their working position, gear wheel 52 is moved away from stop screw 53 whereby the pin heads 47 under the bias of springs 48, slide to the smaller diameter portion of conical ring 44 until, in the opposite end position, the gear 42, the pins occupy the retracted position shown in FIG. 6.

As indicated in FIG. 4, two adjusting pinions 49 may be provided at diametrically opposite locations, in

order to permit a resetting of pins 11 practically in any working position of upper tool 8 of the press.

FIGS. 7, 8, 9 and 10 illustrate the second embodiment of the invention comprising a resetting device 5 generally designated 35a. This embodiment of the invention differs from that already described above insofar as pins 11a are of unequal, progressively increasing length and bear against a regularly sloping circumferential surface 56a of a spiral-shaped disc 56. Disc 56 is 10 carried by a hub designed as a gear 57 and which meshes with an adjusting pinion 49a which is mounted in receiving body 39a so as to be fixed against axial displacement. The fixing may be the same as that described for FIGS. 4 and 5. By means of bolts 58, receiving body 39a is fixedly screwed to a flange 59 of a hub 60 which is secured to shaft 28 by the clamping screw 36a engaging the key.

The smooth cylindrical pins 11a are inserted from the outside into reception bores 61 and are clamped in 20 their respective position. To this end, there are provided tapered clamping or binding bolts 62 each having an oblique surface 63 and guided in a respective larger diameter 64 which is machined transversely of the associated reception bore 61 and at least partially intersects the latter. Bolts 62 seat against disc springs 65 which absorb the clamping force applied against the inserted pins 11a. A tap hole 68, for a back-pressure screw 67, extends from the outside into bore 61.

In the zone of the abrupt change in diameter of spiral surface 56a, at the location indicated by 66 in FIG. 7, the shortest pin which has already been worn down, is replaced by a new one. For this purpose, and as shown in FIG. 10, back-pressure screw 67 is screwed into tap hole 68 of the used pin until the associated tapered binding bolt 62 is released and the pin can be removed. Thereupon, spiral-shaped disc 56 is turned by one pitch in the direction of arrow 69 of FIG. 7 by correspondingly turning adjusting pinion 49a which may be actuated through an internal hexagonal socket head 52a. A new pin 11a is then inserted into the cleared reception bore 61, and has the initial normal length. Thereafter back-pressure screw 67 is screwed out of tap hole 68 so that the newly inserted pin is clamped in its position by the bolt 62. In turning the spiral surface through one pitch, all of the pins are reset and they are subsequently ground to the desired working circle.

In this second embodiment of the invention, two or more adjusting pins may be provided in the same manner as mentioned for the first embodiment, to facilitate resetting of the spiral surface. The second embodiment of the resetting device has the advantage that, in each case, only one pin, that is, the shortest and most worn pin, has to be replaced by a new pin. A further setting time reduction thereby is obtained for the perforation punching tools of a rotary press.

While specific embodiments of the invention have been shown and described in detail to illustrate the application of the principles of the invention, it will be understood that the invention may be embodied otherwise without departing from such principles.

What is claimed is:

1. In a rotary printing press having a device, for punching rows of perforations in continuous paper webs, in the form of rotary punching tools secured to driving shafts and including a first tool provided with re-adjustable punch pins mounted in a receiving body and a cooperating second tool provided with punch

dies, the punch pins being regrindable, by a grinding attachment, to tangency of their working ends with a common circle concentric with the axis of rotation of the first tool; the improvement comprising, in combination, a pin resetting device mounted in said receiving body coaxial with the driving shaft of said first tool and acting simultaneously on all of said pins; and actuating means accessible from the printing press exterior operable to actuate said resetting device to displace all said pins simultaneously through equal radial distances.

2. In a rotary printing press, the improvement claimed in claim 1, in which said rotary printing press includes a frame; said grinding attachment being mounted on a cross beam of said frame for displacement along said cross beam; and a cup-shaped grinding wheel on said grinding attachment adjustable to the re-adjusted pins of said upper tool while said upper tool remains in its working position in the rotary press.

3. In a rotary printing press, the improvement claimed in claim 1, in which said receiving body has an externally threaded hub; an internally threaded gear threadedly engaged with said hub and having an extended hub portion; a ring mounted on said head portion and having a conical external surface concentric with said hub portion; means restraining said ring against axial displacement along said hub portion; said pins having equal lengths and having heads on their inner ends formed with oblique surfaces engageable with said conical surface; springs biasing inner heads of said pins against said conical surface; and a pinion meshing with said gear and rotatable to actuate said resetting device.

4. In a rotary printing press, the improvement claimed in claim 3, in which said pinion is secured to a shaft mounted in said receiving body for rotation and restrained against axial displacement; said pin having an externally projecting polygonal end constituting said actuating means.

5. In a rotary printing press, the improvement claimed in claim 4, including means engageable with said gear and limiting displacement thereof axially of the hub of said receiving body to limit the pin readjustment path of said ring having said conical exterior surface.

6. In a rotary printing press, the improvement claimed in claim 5, in which said limiting means comprises a stop screw threaded through said receiving body to engage said gear and having a lock nut threaded thereon.

7. In a rotary printing press, the improvement claimed in claim 4, including a second pinion meshing

with said gear and secured to a shaft rotatably mounted in said receiving body and held against axial displacement, the last-named shaft having a polygonal outer end to constitute an actuating means; said two pins being arranged at locations on said receiving body which are diametrically opposite each other for selective actuation.

8. In a rotary printing press, the improvement claimed in claim 1, including a cover member having 10 a hub secured to the driving shaft of said first tool, a cover flange extending radially from one end of said hub, and a cylindrical lip extending axially from the outer end of said radial flange toward the opposite end of said hub; said receiving body being secured to said 15 radial flange; a spiral-shaped disc mounted on said hub for rotation thereon and having a hub portion formed as a gear; said pins being mounted in circumferentially spaced radial bores in said axially extending cylindrical lip; said spiral-shaped disc having a spiral external periphery with a regular gradient; said pins having respective different lengths and being of uniform cross section throughout, with the differences in the length of said pins being equal to each other and corresponding to the 20 circumferential spacings of said pins and to the gradient of said spiral external periphery of said disc; the inner ends of said pins engaging said spiral-shaped periphery of said disc; and a pinion rotatably mounted in said receiving body and meshing with said gear to rotate said disc.

9. In a rotary printing press, the improvement claimed in claim 8, including respective clamping devices retaining each pin in its associated radial bore; said pinion being secured to a shaft rotatably mounted in said receiving body and fixed against axial displacement therein, said shaft constituting actuating means for said disc.

10. In a rotary printing press, the improvement claimed in claim 9, in which said flange is formed with respective axially extending bores each intersecting a 40 pin receiving bore; respective tapered clamping bolts, having oblique surfaces, mounted in said axially extending bores; respective disk springs at the inner ends of said axially extending bores biasing the associated clamping bolts into wedging clamping relation with the associated pin; and a respective tap hole at the outer end of and coaxial with axially extending bore to receive a back-pressure screw for threading thereinto to engage the associated clamping bolt to move the same inwardly against the bias of the respective spring to release the associated pin.
